[57] **CLAIM**

The ornamental design for a display device, as shown and described.

DESCRIPTION

FIG. 1 is a front perspective view of a display device showing the new design of the present invention;

FIG. 2 is a front elevational view thereof;

FIG. 3 is a rear elevational view thereof;

FIG. 4 is a left end view thereof, which view is identical to a right end view thereof;

FIG. 5 is a top plan view thereof, which is identical to a bottom plan view thereof;

FIG. 6 is a rear elevational view thereof;

FIG. 7 is a rear elevational view of the display device device of FIG. 1 showing an alternative embodiment of a hanging device for the display device;

FIG. 8 is a rear elevational view of the display device of FIG. 1 showing an alternative embodiment of a hanging device for the display device;

FIG. 9 is a rear elevational view of the display device of FIG. 1 showing an alternative embodiment of a hanging device for the display device;

FIG. 10 is a front elevational view of the display device of FIG. 1 showing an alternative embodiment of a hanging device for the display device; and,

FIG. 11 is a front elevational view of the display device of FIG. 1 showing a mounting arrangement for the device.
